FIGURE 1 is a front elevation of a fireplace incorporating our new design.

FIGURE 2 is a rear elevation thereof.

FIGURE 3 is a top plan thereof.

FIGURE 4 is a bottom plan thereof.

FIGURE 5 is an end elevation thereof.

FIGURE 6 is a front elevation of a fireplace incorporating a modified form of our new design.

FIGURE 7 is a rear elevation of FIG. 6.

FIGURE 8 is a fragmentary top plan of FIG. 6.

FIGURE 9 is a fragmentary end elevation of FIG. 6.

FIGURE 10 is a front elevation of a fireplace incorporating a further modified form of our new design.

FIGURE 11 is a fragmentary top plan of FIG. 10.

FIGURE 12 is a front elevation of a fireplace incorporating a further modified form of our new design.

FIGURE 13 is an end elevation of FIG. 12.

For convenience of illustration, FIGURES 8, 9 and 11 are fragmentary; i.e., partly broken away. The shield and flue elements are broken away to indicate indeterminate length.

We claim:

The ornamental design for a fireplace, as shown and described.
